William Resor, of Cincinnati, Ohio.

Letters Patent No. 800. Dated June 3. 1856

The schedule referred to in these Letters Patent and making part of the same.

To all whom it may concern:

Be it known that I, William Resor, of Cincinnati, Hamilton County, Ohio, have invented a new design for a Cooking Stove, called the "Kentucky", and I do hereby declare that the following is a full and exact description thereof, reference being had to the annexed drawings making part of this specification.

In the accompanying drawings
Fig. 1. is a perspective view of my stove.
Fig. 2, represents one of the oven doors.
Fig 3, a vertical section of the same.

Fig 4. one of the front doors.

Fig 5. is the end fire door

Fig 6. is a part view of a leg.

The moulding (represented in outline in fig 3)
is the same on all the doors.

The central space of each door is ornamented
by reeding (a) as represented. The upper portion of the leg has
also a similar reeding (b). Below this reeding occurs a fleur-de-lis (c)

I claim the design for the "Kentucky" cooking
stove substantially as described and represented.

In testimony whereof I hereunto set my
hand before two subscribing witnesses.
